UNITED STATES PATENT OFFICE

GEORG BALZ, OF GLEIWITZ, GERMANY

FURNACE FOR ROASTING ZINC BLENDE

Application filed July 7, 1926, Serial No. 121,010, and in Germany December 5, 1925.

This invention relates to a furnace for roasting zinc blende.

In particular, the invention deals with a furnace which is traversed by the blende from the top towards the bottom, and in which the blende is washed by furnace air moving in the opposite direction, whereby merely a portion of the air is introduced as the material is discharged from pre-heated chambers situated at the hearth level, and the remainder supplied in the form of cool, fresh air through passages beneath the arch of the furnace, striking against the material falling freely out of the central opening of the hearth, in this manner any parts endangered by the heat being cooled, sintering and agglomeration of the blende prevented, and the material made better suitable for purposes of smelting.

Now it is desirable for the draft in the furnace to be maintained as constant as possible. Particularly in the case of the floors or compartments at which the blende moves in an upwardly inclined direction it is shown that by reason of the known method of conveying the material and transferring the same from the one floor to that located thereunder, which is effected by means of vanes or the like of refractory material mounted at the top of each compartment, mounds or accumulations of blende very readily tend to form, which extend as far as the top of the compartment and choke the draft, so that the proper functioning of the furnace is very greatly affected, or even rendered impossible. A regular draft in the furnace is absolutely necessary both as regards quality as well as quantity of the product.

The main object of the invention is to ensure that a proper draft is maintained, this being accomplished by providing on the roof of the arch scrapers which, when accumulations are formed strike off the mounds and at the same time better distribute the material.

The secondary air is introduced from above or from below or from the side towards a slotted cage in the inner passage where the material changes its direction. The air now meets from the inside not only against the mate-

rial falling freely through the hearth opening, but also against the sliding material moving towards the passage, the action of the air thus being considerably increased and improved. The secondary air if coming from the top is preferably introduced through a feed pipe passed through the gas discharge, the same being taken through an opening in the arch above the centre passage, and, as stated above, furnished at its slower end with a suitable, slotted cage through which the air is emitted. The slotted cage is preferably normally closed at the bottom in order to prevent the air from passing out in an axial direction and to compel the same to pass out laterally in order, proceeding from the interior, to meet on all sides against the material falling through annularly and against the material conveyed towards the opening. This method of supplying the air assists also to improve the draft.

If the air is introduced to the distributing member from the bottom or from the side, the feed pipe may be passed through the furnace at any desired point, and the arrangement may be of such kind that branch pipes, each capable of regulation per se, may be attached to the vertically or obliquely disposed main supply pipe, so that air may be passed from the one or other point according to requirements to the distributor, and accordingly against the blende in the furnace; or a mixture of air may be introduced as determined by manipulation of the regulators. If necessary, introduction of the air in a lateral direction may also be combined with introduction from below, or also from above.

A form of embodiment of the invention is illustrated by way of example in the accompanying drawings, in which

Figure 1 is a vertical section of the furnace.

Figure 2 is a cross-sectional view of the furnace on line 2-2, Fig. 1.

Figure 3 is a vertical section of the cage on line 3-3, Fig. 5.

Figure 4 is a vertical section of the furnace showing a modification thereof.

Figure 5 is a cross-sectional view on line 5-5 of Figure 3.

With reference to Fig. 1, the blende passes

from compartment to compartment through the openings 7 and 9. On the roof of the arch are furnished in known manner vanes or other conveying means 6 for moving the blende towards the openings 7 and 9. The furnace comprises discs 11, 12, 13, 14 and 15 which form compartments and which are made of any suitable refractory material. Alternate discs 11, 13 and 15 are stationary and are supported by columns 10. Discs 12 and 14 are rotatably mounted on tracks 18 by means of rollers 17, said discs are encircled by toothed driving rings 16. A shaft 19 rotated by any suitable means has pinions 20 keyed thereon so that discs 12 and 14 may be rotated. Said conveying means 6 which may have a wedge formation are mounted on the underside of all discs except disc 15. In the case of the compartments in which the blende moves in an upwardly inclined direction, i. e., towards the opening 9, accumulations are very easily formed which may extend right to the top of the compartment, and which then choke the draft and considerably affect operations, or even block the furnace.

An essential feature of the invention resides in the provision of the scrapers 35, which are so arranged that they strike off the tops of any accumulations formed, and thus ensure that the draft is constantly maintained. Said scrapers have a wedge shaped form and are affixed to the underside of all discs except disc 15 behind the vanes 6 (see Fig. 2). These scrapers may be of any desired form or length, adapted to suit requirements.

According to Fig. 1 an air supply pipe 36 is passed through the upper compartment 5 and the arch thereof, being taken through the gas discharge 30 and made to be movable in any suitable manner at 37. The pipe 36 may open out in front of the central opening 9, or may be extended to any desired degree within the same. At the lower end of 36 is situated a slotted cage 38, through the slots 42 of which the air is forced on all sides in the desired direction, this cage being preferably closed at the bottom in order to prevent the air from passing out in an axial direction. The air strikes against the material falling in annular form at 9, and also against the blende being conveyed towards 9, and the cooling effect is greatly improved. The cage may be of any desired size, or the same may also comprise the lower end of the feed pipe itself.

In the form of embodiment according to Fig. 3 the end of the pipe 36, or a tubular portion affixed thereto, is slotted or cut longitudinally, and the tongues 43 so formed are secured by means of rings applied either interiorly or exteriorly, these rings being designated 39. An opening in the bottom of the skirt is closed by means of a temporary in-

sertion ball 40, so that the cage may be cleaned from below by introduction of an air blast and displacement of said ball 40.

According to Fig. 4, the air may be introduced from below (pipe 36), or from the side (pipe 31), either terminating in the slotted cage 38'. The pipe 36 may be bent at a suitable angle, or branch pipes 41, may be provided in any desired number, which are furnished with regulating members 33, and through which the secondary air may be introduced at suitable pressure.

What I claim as new and desire to secure by Letters Patent is:

1. In a furnace for roasting zinc blende, in combination, a plurality of circular refractory discs placed in spaced relation to form intervening chambers, means for rotating alternate discs, wedge shaped vanes positioned on the lower surfaces of said discs and scrapers positioned on said discs for destroying accumulations of the blende.

2. In a furnace for roasting zinc blende, in combination, a plurality of circular refractory discs placed in spaced relation to form intervening chambers, means for rotating alternate discs, wedge shaped vanes positioned on the lower surfaces of said discs, scrapers positioned on said discs for destroying accumulations of the blende and a means for introducing air directly into the furnace at the axis thereof.

3. In a furnace for roasting zinc blende, in combination, a plurality of circular refractory discs placed in spaced relation to form intervening chambers and provided with a plurality of openings, means for rotating alternate discs, an air supply pipe coaxial with respect to said furnace, a cage positioned on the discharge end of said air supply pipe, a gas discharge pipe communicating with said intervening chambers, vanes and scrapers positioned on said discs to propagate the blende and destroy accumulations thereof respectively.

4. In a furnace for roasting zinc blende, in combination, a plurality of circular refractory discs placed in spaced relation to form intervening chambers and provided with a plurality of openings, means for rotating alternate discs, an air supply pipe coaxial with respect to said furnace, a cage positioned on the discharge end of said air supply pipe, said cage being provided with a plurality of vertical slots forming tongues, a plurality of rings engaging said tongues, a gas discharge pipe communicating with said intervening chambers, vanes and scrapers positioned on said discs to propagate the blende and destroy accumulations thereof respectively.

5. In a furnace for roasting zinc blende, in combination, a plurality of circular refractory discs placed in spaced relation to form intervening chambers and provided with a

plurality of openings, means for rotating alternate discs, an air supply pipe coaxial with respect to said furnace, a cage positioned on the discharge end of said air supply pipe, 5 said cage being provided with a plurality of vertical slots forming tongues, said cage being further provided with a hole in the bottom thereof and a ball adapted to normally close said cage, a gas discharge pipe communicating with said intervening chambers, 10 vanes and scrapers positioned on said discs to propagate the blende and destroy accumulations thereof respectively.

In testimony whereof I have affixed my
15 signature.
